[57] CLAIM

The ornamental design for a bushing puller, as shown
and described.

DESCRIPTION

FIG. 1 is a front perspective view of a bushing puller,
showing my new design;

FIG. 2 is a side elevational view thereof, the opposite
side being a mirror image;

FIG. 3 is a top plan view thereof, the bottom view being
identical except for the keyway which is absent therein;
FIG. 4 is an enlarged front elevational view thereof
with the expansion head shown in fully expanded position;

FIG. 5 is an enlarged rear elevational view thereof;

FIG. 6 is an enlarged fragmentary side elevational view
thereof, showing the expansion head in fully contracted
position; and,

FIG. 7 is an enlarged fragmentary side elevational view
thereof, showing the expansion head in fully expanded
position.

FIG. 1.

FIG. 3.

FIG. 2.

FIG. 4.

FIG. 5.

FIG. 7.

FIG. 6.
